UNITED STATES PATENT OFFICE.

WILLARD F. WILSON, OF WEST HOBOKEN, NEW JERSEY.

IMPRESSION-HOLDER.

1,018,466.

Specification of Letters Patent. Patented Feb. 27, 1912.

Application filed July 29, 1911. Serial No. 641,189.

To all whom it may concern:

Be it known that I, WILLARD F. WILSON, a citizen of the United States, residing at West Hoboken, Hudson county, New Jersey, 5 have invented certain new and useful Improvements in Impression-Holders, of which the following is a full, clear, and exact description.

My invention relates to an improved holding device for holding plaster and the like, for the purpose of obtaining impressions of teeth as well as the "bite" thereof.

The object of the invention is to provide a very simple and effective holding device 15 for this purpose, which from a reading of the following specification and an examination of the accompanying drawings, will be seen to possess many advantages.

In the drawings Figure 1 is a plan view 20 of the holder assembled with a block of plaster therein bearing an impression. Fig. 2 is a view of the reverse side of Fig. 1. Fig. 3 is a perspective view of the holder. Fig. 4 is a plan view of one side plate of 25 the holder. Fig. 5 is a plan view of the connecting element and the other side plate. 1-2 represent two side plates of proper design to embrace between them and hold the plastic material which is to receive the 30 impression. The side plate 1 preferably has a handle portion 3. In the preferred form of construction the plates 1-2 are connected by a U-shaped connecting member 4, which preferably makes a sliding connection 35 with each of the side plates 1-2, whereby the connecting member may be slid off both plates after the impression is taken, thus leaving the said plates free to be easily removed from the plaster impression without 40 injury to the same. The plate 1 preferably has a longitudinal slot or groove 1^a, and the side plate 2 preferably has a longitudinal slot or groove 2^a. These slots or 45 grooves may enter from either end as desired, and the shoulders at the edges of said grooves constitute a convenient support for a sheet of wax, which may be used to facilitate the separation of the upper and lower impression sections of the plaster. In the 50 use of the device for obtaining the double impression and "bite", a sheet of wax would be inserted in the aforesaid grooves so as to stand horizontally. The plaster, in a proper condition, is then applied above 55 and below the wax, said plaster, if desired, overlapping and connecting slightly at the

ends to hold the material in block. The holder is then inserted into the mouth at either side, as desired, since the connector for the side plates is located at the rear of 60 the alveolar ridge, or rearmost teeth, it avoids interference and enables the one who is having the impression taken to close down tightly. After the impression is taken, it will be found that the "bite" will occur 65 along the line of the wax, and hence when the block is removed the upper and lower sections may be easily separated so as to give respectively an impression of the upper and lower teeth and alveolar ridge, in the event 70 of missing teeth, as well as the "bite" of said teeth.

In various ways I appreciate that this construction which I have described in its preferred form only, may be modified without departing from the spirit or scope of the 75 invention.

In the drawings, I have shown the slide connection between the connector 4 and the two side plates 1-2 formed by a long flat 80 eye 5 on the back of each plate through which the flattened ends of the connector project.

What I claim is:

1. In an impression holder, two side 85 plates for supporting between them material in which an impression is to be made, and a bowed connector for both of said plates and arranged at one end thereof.

2. In an impression holder, two side 90 plates for supporting between them material in which an impression is to be made, a bowed connector for both of said plates and arranged at one end thereof, and a detachable connection between said bowed connector and one of said plates. 95

3. In an impression holder, two side plates for supporting between them material in which an impression is to be made, a bowed connector for both of said plates and 100 arranged at one end thereof, and a detachable connection between said bowed connector and both of said plates.

4. In an impression holder, two side plates for supporting between them material in which an impression is to be made, a connector for both of said plates and arranged at one end thereof, and a supporting shoulder extending horizontally in one 105 of said plates for supporting a sheet of wax 110 or the like.

5. In an impression holder, two side

plates for supporting between them material in which an impression is to be made, a connector for both of said plates and arranged at one end thereof, and a supporting shoulder extending horizontally in one of said plates for supporting a sheet of wax or the like, said supporting shoulder being formed by a slot in said plate.

6. In an impression holder, two side members for holding between them material in which an impression is to be made, a bowed connector for said side members located at the rear end of said side plates to leave the space between said plates free and unobstructed.

7. In an impression holder, two side members for holding between them material in which an impression is to be made, a bowed connector for said side members located at the rear end of said side plates to leave the space between said plates free and unobstructed, and a slide connection between said bowed connector and both of said plates whereby said connector can be removed from said plate to free the same.

WILLARD F. WILSON.
